DESIGN FOR A LAMP

Edwin A. Koch, River Edge, N. J.

Application January 25, 1937, Serial No. 67,270

Term of patent 3½ years

To all whom it may concern:

Be it known that I, Edwin A. Koch, a citizen of the United States, residing at River Edge, in the county of Bergen and State of New Jersey, have invented a new, original, and ornamental Design for a Lamp, of which the following is a specification, reference being had to the accompanying drawing, forming part thereof.

Fig. 1 is a side elevational view of a lamp showing my new design; Fig. 2 is a top plan view thereof; and Fig. 3 is a rear end view thereof.

I claim:

The ornamental design for a lamp as shown.
EDWIN A. KOCH.
